Atty.

UNITED STATES PATENT OFFICE.

LOUIS COATALEN, OF WOLVERHAMPTON, ENGLAND, ASSIGNOR OF ONE-HALF TO
SUNBEAM MOTOR CAR COMPANY LIMITED, OF WOLVERHAMPTON, ENGLAND.

LUBRICATION SYSTEM FOR INTERNAL-COMBUSTION ENGINES.

1,253,940.

Specification of Letters Patent. Patented Jan. 15, 1918.

Application filed June 12, 1916, Serial No. 103,321. Renewed July 6, 1917. Serial No. 179,098.

To all whom it may concern:

Be it known that I, LOUIS COATALEN, a subject of the King of Great Britain, residing at Wolverhampton, in the county of Stafford, England, have invented certain new and useful Improvements in Lubrication Systems for Internal-Combustion Engines, of which the following is a specification.

10 This invention relates to lubrication systems for internal combustion engines of the kind in which a pump or pumps is or are employed for circulating the oil.

In the accompanying drawings,

15 Figure 1 is an end view partially in section, showing one method of carrying out this invention.

Fig. 2 is a cross section on the line 2—2 of Fig. 1, but showing also the oil filter which 20 does not appear in Fig. 1.

Fig. 3 is a horizontal section on the line 3—3 of Fig. 2.

Like letters indicate like parts throughout the drawings.

25 In most engines the crank chamber is divided horizontally and the lower part is easily removable for access to the bearings, etc. It is desirable that the oil pump should be carried by the more rigid upper part, but 30 the oil collects in the lower part and there must be a connection between the oil chamber in the lower and the oil pump on the upper part.

It is the object of the present invention 35 to provide an improved connection, which is particularly applicable where a double oil pump is used, one half drawing the oil from the supply and forcing it to the bearings, and the other delivering the used oil back to 40 the supply tank.

The upper part A of the crank chamber carries the cylinders and main engine shafts, from one of which, A², is driven a vertical spindle A³ which drives a pair of gear wheel 45 pumps contained in the superposed casings B and C. These casings are bolted together, and the upper one is attached by bolts, one of which is shown at B², to the upper part A of the crank chamber. The oil in the 50 crank chamber collects in the lower crank chamber part D which is formed with a well E. The used oil collecting in this well enters the lower pump casing C, (see Figs. 2 and 3) and is driven by this pump down 55 along the outlet pipe C², and out through

the pipe C³ to the oil tank or cooler which is arranged outside the engine.

The pump contained in the upper casing B sucks oil from the tank along the passage F¹ from an inlet chamber F supplied by the branch F², and delivers this by the passage F³ to the various parts of the engine which require lubrication.

It will be seen that oil traveling down the passage C² enters an oil chamber C⁴ provided with a drain plug C⁵. The oil chamber F may be constructed as a filter chamber, as shown, and if desired the chambers F and C⁴ may be formed integral with one another, and they are attached to the lower 70 part D of the crank chamber. When this lower part is detached it is clear that the connection between the passage C² and the chamber C⁴, and the passage F⁴ with the chamber F, must be broken.

To facilitate this the following construction is adopted:—Each of the pipes C² and F⁴ carries a washer H which is pressed upward by a spring J which abuts against a collar K fixed to the pipe C² or F⁴. Between the washer H and the upper wall of the oil chamber is arranged a ring of packing material. This spring-pressed washer, in conjunction with the packing material provides an oil-tight connection, but there is a clearance between the side of each pipe and the side of the hole in the oil chamber through which it passes so that the pipes have a certain amount of lateral freedom and consequently relative vibration between 90 the two crank chamber parts does not throw any strain on this connection. This clearance is too small to be apparent in the drawings.

It will be clear that removal of the crank chamber part D is possible without disturbing the oil pumps. Further, that there is no difficulty in insuring an oil tight connection which is not affected by vibration.

What I claim as my invention and desire 100 to secure by Letters Patent is:—

1. In an internal combustion engine, the combination of an upper crank chamber part, a lower part detachable therefrom, an oil pump carried by said upper part, an oil chamber carried by said lower part, and a floating oil-tight connection between said pump and said oil chamber, substantially as set forth.

2. In an internal combustion engine, the 110

combination of an upper crank chamber part, a lower part detachable therefrom, an oil pump carried by said upper part, an oil chamber carried by said lower part, an oil pipe carried by said pump, a clearance hole in said oil chamber through which said oil pipe passes, a spring pressed washer on said oil pipe, substantially as set forth.

3. In an internal combustion engine, the combination of an upper crank chamber part, a lower part detachable therefrom, a pair of superposed oil pumps carried by

said upper part, a pair of oil chambers carried by said lower part, floating oil-tight connections between each of said pumps and 15 one of said oil chambers, substantially as set forth.

In testimony whereof I have signed my name to this specification in the presence of two subscribing witnesses.

LOUIS COATALEN.
